BELL

Clyde W. Garthwait, Waterbury, Conn., and Vincent Turner, Bronxville, N. Y., assignors to Cly-Del Mfg. Co., Waterbury, Conn., a corporation of Connecticut

Application February 12, 1949, Serial No. 76,044

5 Claims. (Cl. 116—150)

1

This invention relates to bells, and more particularly to a bell which has a shape of the flared or "Liberty bell" type, and which is adapted to be economically formed from sheet metal.

One object of this invention is to provide a complete bell of the above nature consisting of only two interconnected sheet metal parts which require no additional parts for their securement.

Another object is to provide a bell of the above nature wherein the tongue-supporting and bell-supporting means are provided by adjacent inner and outer loops which may be struck out of the body portion of the bell in a single machine operation.

Another object is to provide a bell of the above nature wherein the tongue may be attached to the body portion in a simple operation which will require no additional parts and no special tools.

Another object is to provide a bell of the above nature in which the body portion may be drawn from sheet steel, and which when struck by the tongue, will emit a clear musical tone.

A further object is to provide a bell of the above nature which will be simple in construction, inexpensive to manufacture, easy to assemble and manipulate, compact, ornamental in appearance, and very efficient and durable in use.

With these and other objects in view, there has been illustrated on the accompanying drawing one form in which the invention may conveniently be embodied in practice.

In the drawing,

Fig. 1 is a front view of the improved bell.

Fig. 2 is a similar front view, partly in section, showing the interior construction.

Fig. 3 is a side view of the same, partly in section.

Fig. 4 is a fragmentary perspective view of the inner end portion of the tongue, on an enlarged scale, showing the split eye as it would appear in its initial form before the tongue is assembled with the body portion.

Referring now to the drawing, in which like reference numerals denote corresponding parts throughout the several views, the numeral 10 indicates a hollow body portion which comprises a substantially flat circular top section 11, the periphery of which is slightly rounded and drawn downwardly into a depending upper cylindrical portion 12. The cylindrical portion 12 preferably constitutes at least one-third of the height of the bell, and extends downwardly into a flared mouth portion 13, which terminates in a narrow vertical substantially cylindrical smooth-edged bottom rim 14.

2

A spaced pair of curved loops 15, 16 are struck upwardly from the central portion of the circular top section 11 in order to serve as means for suspending the bell from a suitable support—a curved intermediate loop 17 being struck downwardly from said top section 11 in order to serve as means for supporting a clapper tongue 18. The loops 15, 16 and 17 are preferably of the same size, and immediately adjacent each other.

10 The tongue 18 is formed of sheet metal and comprises a striker or clapper 19 shaped in the form of a cup having an integral stem 20 extending upwardly from one edge thereof. The bottom end of the stem 20 is offset laterally so as to bring the striker 19 into a centered position in alignment with the upper part of said stem 20 in the body portion 10, and is of a suitable length to support the striker 19 normally in a position where it will project slightly below the body portion 10 to produce the most efficient bell striking operation.

15 The upper end of the stem 20 is provided with an integral circular eye 21 which is split at its upper extremity so as to provide side portions 22, 23, which will be initially located out of the plane of said eye, in offset relation as shown in Fig. 4.

In assembling the tongue 18 of the bell with the body portion 10 thereof, the offset eye portions 20 22, 23 may be easily engaged around the inner tongue supporting loop 17 of the bell, after which the eye 21 will be closed by flattening said offset portions 22, 23 into coplanar relation as shown in Figs. 2 and 3. This closing operation may be 25 easily accomplished merely by twisting the tongue 18 manually, or if desired, any suitable pliers may be inserted into the body portion 10 and employed to press the offset eye portions 22, 23, together.

30 It will be apparent that both the body portion 10 and the tongue 18 may be formed from sheet metal by simple bending and drawing operations. Also each of these parts 10 and 18 may be completely formed in an ordinary eyelet machine 35 without intervening manual operations.

The material employed in producing the body 40 10 and the clapper 19 will preferably have a thickness which is approximately proportional to the size of the bell. It has been found, for example, that when the bell is one inch in diameter, the body 10 and clapper 19 of .012" sheet steel will be very satisfactory, and will produce a bell having a clear musical tone.

45 While there has been disclosed in this specification one form in which the invention may be

embodied, it is to be understood that this form is shown for the purpose of illustration only, and that the invention is not to be limited to the specific disclosure, but may be modified and embodied in various other forms without departing from its spirit. In short, the invention includes all the modifications and embodiments coming within the scope of the following claims.

Having thus fully described the invention, what is claimed as new and for which it is desired to secure Letters Patent is:

1. In a bell, a tongue, a body portion having a top section of sheet material, and separate inwardly and outwardly struck loops disposed centrally of said top section for supporting the tongue and the bell respectively, said loops being integral with said top section. 15

2. In a bell, a body portion having a top section of sheet material, a tongue-supporting loop struck inwardly from the center portion of said top section, and a pair of outer bell-supporting loops separately struck outwardly from said top section at opposite sides of said tongue-supporting loop, said loops being integral with said top section. 20

3. In a bell, a tongue, a body portion of sheet material having a substantially flat top section, and a plurality of similar immediately adjacent central loops separately struck from the material of said top section and integral therewith, one of said loops extending upwardly from the body portion for supporting the bell, and another of 25

5 said loops extending downwardly in said body portion and constituting a means for suspending the tongue.

4. The invention as defined in claim 3 in which said downwardly-extending loop is aligned with a space between two upwardly-extending loops.

5. The invention as defined in claim 3, in which the upper end of the tongue is provided with an eye for embracing said downwardly-extending loop, said eye being split at its inner extremity whereby the assembly of the tongue with the body portion will be facilitated.
